CLAIM

We claim the ornamental design for a digital photography album, as shown and described.

DESCRIPTION

FIG. 1 is a perspective view of the present invention with a cover in an open position, including features shown in phantom lines that are not part of the claimed design.

FIG. 2 is a perspective view of the present invention with the cover in a closed position, including features shown in phantom lines that are not part of the claimed design.

FIG. 3 is a top plan view of the present invention, with the cover in the open position, including features shown in phantom lines that are not part of the claimed design.

FIG. 4 is a top plan view of the present invention, with the cover in the closed position, including features shown in phantom lines that are not part of the claimed design.

FIG. 5 is bottom plan view of the present invention, with the cover in the closed position, including features shown in phantom lines that are not part of the claimed design.

FIG. 6 is a right-side elevation view of the present invention, including features shown in phantom lines that are not part of the claimed design; and,

FIG. 7 is a left-side elevation view of the present invention, including features shown in phantom lines that are not part of the claimed design.
